SPECIFICATION forming part of Design No. 36,470, dated August 4, 1903.

Application filed June 24, 1903. Serial No. 162,970. Term of patent 3½ years.

To all whom it may concern:

Be it known that I, EMIL BÄCHLE, a subject of the Emperor of Germany, and a resident of Meriden, in the county of New Haven and State of Connecticut, have invented a new, original, and ornamental design for Ornaments for Vessels or Similar Articles, of which the following is a brief specification, reference being had to the accompanying drawing, forming a part thereof, for special distinguishing features of the design, and in which the figure is a plan or face view in two

sections of a metal ornament embodying my new design, the section or figure on the right being a continuation of the lower end of the 15 section on the left, as indicated.

What I claim as my invention, and desire to secure by Letters Patent, is—
